UNITED STATES PATENT OFFICE

FRANK L. BAMPFORD AND ALOIS L. MARTINEK, OF DETROIT, MICHIGAN, ASSIGNEES
TO C. M. HALL LAMP COMPANY, OF DETROIT, MICHIGAN, A CORPORATION OF
MICHIGAN

LAMP

Application filed May 26, 1930. Serial No. 455,805.

This invention relates generally to lamps and refers more particularly to cowl lamp assemblies.

Heretofore the bodies of cowl lamps have been secured to their supporting brackets and the latter have been secured to the cowl in such a way that it was difficult when inaccuracies occurred in any of these parts to properly position the lamp bodies so that the front faces thereof were in alignment at the proper angle or inclination relative to the cowl. Therefore it is an object of the present invention to provide the lamp body and its supporting bracket with an adjustable connection which will compensate for any irregularities or inaccuracies and will enable the lamp bodies to be adjusted relative to their supporting brackets so that the front face of the lamps may be in alignment at the proper angle or inclination relative to the cowl.

Another object is to provide a connection that permits the lamp body to be adjusted easily and quickly after the parts are assembled on the cowl and that will effectively hold the lamp body in any adjusted position.

With the above and other objects in view the invention consists of certain novel features of construction, combinations and arrangements of parts that will be hereinafter more fully described and particularly pointed out in the appended claims.

In the accompanying drawings:

Figure 1 is a fragmentary elevation of a vehicle body with cowl light assemblies embodying our invention mounted thereon;

Figure 2 is a front elevation of one of the cowl lamp bodies with the door removed;

Figure 2A is a bottom plan view of the body shown in Figure 2;

Figure 3 is a sectional view through the lamp body shown in Figure 2;

Figure 4 is a detail view of the supporting bracket;

Figure 5 is a detail view of the attaching plate;

Figure 6 is a view similar to Figure 2 but showing a slightly modified construction;

Figure 7 is a sectional view taken on the line 7—7 of Figure 6;

Figure 8 is a bottom plan view of the body shown in Figures 6 and 7.

Figure 9 is a perspective view of the bracket for the lamp illustrated in Figures 6 to 8 inclusive.

Referring now to the drawings, 1 is a lamp body; 2 is a supporting bracket therefor; 3 and 4 are attaching screws extending upwardly from the bracket; 5 is an attaching plate of relatively heavy gage metal receiving the screws and adjustably mounted upon the inner face of the body; 6 is a retainer plate of relatively light gage metal for the attaching plate; and 7 and 8 respectively are rivets securing the retainer plate to the body.

As shown, the bracket 2 is secured in the usual manner to the cowl 9 of a vehicle body and has the usual central bore 10 for receiving the lamp bulb electrical conduits (not shown). The lamp body 1 is provided with an opening 11 for receiving the electrical conductors just mentioned and is provided at substantially diametrically opposite points of said opening with circular openings 12 and 13 for receiving the screws 3 and 4. In the present instance however these openings 12 and 13 are quite large and permit the body 1 to be shifted laterally relative to the screws 3 and 4. The plate 5 is preferably substantially diamond shaped in form and conforms to the curvature of the inner face of the lamp body. As shown, this plate has threaded openings 14 and 15 respectively for receiving the screws 3 and 4 and has relatively large circular openings 16 and 17 respectively that receive the rivets 7 and 8. The retainer plate 6 conforms to the curvature of the inner face of the attaching plate 5 and is substantially circular in form. The rivets 7 and 8 hold the retainer plate 6 immovable and clamp the same upon the attaching plate 5 in such a way that the frictional engagement between the parts is sufficient to hold the lamp body in any adjusted position.

In use when the parts are assembled the lamp body 1 may be readily adjusted by hand relative to the attaching plate 5, screws 3 and 4, and bracket 2 so that the front face of the lamp will be at the proper angle or inclination with respect to the cowl. Thus with

this construction the lamps upon opposite sides of the cowl may be readily and accurately aligned after they have been mounted upon their supporting brackets.

In Figures 6 to 8 inclusive we have shown a slight modification in which a substantially triangular plate 20 is adjusted upon the inner face of the body 21 and is held in adjusted position by a plate 22 and rivet 23. As shown, the plate 20 has three threaded openings 24, 25 and 26 respectively that register with three larger circular openings 27, 28 and 29 respectively in the lamp body and receive suitable attaching screws (not shown) that extend through openings 41, 42 and 43 respectively in the supporting bracket 44. The retainer plate 22 has a circular opening 30 registering with openings 31 and 32 respectively in the plate 20 and lamp body and has a narrow extension 33 that is received between struck-out lugs 34 and 35 at the outer edge of the body and is provided with a threaded opening 36 for receiving the securing element 37 for the lamp door 38. Thus with this construction the retainer plate 22 serves a dual function.

While it is believed that from the foregoing description the nature and advantages of the invention will be readily apparent, we desire to have it understood that we do not limit ourselves to what is herein shown and described, and that such changes may be resorted to when desired as fall within the scope of what is claimed.

What we claim as our invention is:

1. In a lamp assembly, a lamp body, and a plate having an opening for receiving an electrical conductor and having a portion at an edge of the body provided with a threaded opening for receiving securing means for a door for the body.

2. In a lamp assembly, a lamp body, a support therefor, and a connection between said support and body permitting the body to be adjusted relative to the support, including a plate fixed in spaced relation to the body, and a plate frictionally engaging the plate and body and adjustable relatively to the support.

3. In a lamp assembly, a lamp body support, a lamp body on the support, and a connection between said lamp body and support permitting the body to be shifted laterally relative to the support, including securing elements projecting from the support through openings in a wall of the body, securing elements projecting from said wall, a plate held by the last mentioned securing elements in spaced relation to the wall, and a plate frictionally engaging the wall and plate and having openings receiving the first and last mentioned securing elements.

4. In a lamp assembly, a lamp body support, a lamp body on the support, and a connection between said lamp body and support

70 permitting the body to be shifted laterally relative to the support including securing elements projecting from the support through a wall of the body, securing elements projecting from said wall, a plate frictionally engaging the wall and receiving the first mentioned securing elements, and a plate held by the second mentioned securing elements and frictionally engaging the first mentioned plate.

5. In a lamp assembly, a lamp body support, a lamp body on the support, and a connection between said lamp body and support permitting the body to be shifted laterally relative to the support including securing elements projecting from the support through a wall of the body, securing elements projecting from said wall, a plate held by the last mentioned element in spaced relation to the wall, and a plate receiving the first mentioned securing element and frictionally engaging both said wall and first mentioned plate.

6. In a lamp assembly, a lamp body support, a lamp body on the support, and a connection between said body and support permitting the body to be adjusted relative to the support, including securing elements projecting from the support through a wall of the body, a plate within the body and fixed in spaced relation to said wall, and a plate receiving the securing elements aforesaid and frictionally engaging the wall and plate aforesaid.

7. In a lamp assembly, a lamp body support, a lamp body on the support, and a connection between said body and support permitting the body to be adjusted laterally relative to the support, including securing elements projecting from the support through a wall of the body, a plate frictionally engaging said wall and receiving the securing elements, and means associated with said wall and frictionally engaging the plate whereby it may be adjusted relative to the wall but may be held in any adjusted position.

In testimony whereof we affix our signatures.

FRANK L. BAMFORD.
ALOIS L. MARTINEK.
